WILLIS PENNINGTON, OF INTERLOCHEN, MICHIGAN.

IGNITER AND VALVE MECHANISM.

1,225,681.

Specification of Letters Patent.

Patented May 8, 1917.

Original application filed February 17, 1913, Serial No. 749,041. Divided and this application filed April 13, 1914. Serial No. 831,597.

To all whom it may concern:

Be it known that I, FREDERICK E. RUPRIGHT, a citizen of the United States, residing at Interlochen, in the county of Grand 5 Traverse and State of Michigan, have invented a new and useful Igniter and Valve Mechanism, of which the following is a specification.

The device forming the subject matter of 10 this application is an internal combustion engine, and one object of the invention is to provide an engine of this sort, in which two cylinders are located upon opposite sides of the crank shaft and coact to impart rotation 15 thereto, thereby increasing the power of the engine.

Another object of the invention is to provide an internal combustion engine which will operate without jarring and in a balanced condition.

A further object of the invention is to provide novel means for timing the explosion and for controlling the exhaust. The invention aims to provide novel means for controlling and regulating the character of the explosive mixture.

It is within the scope of the invention to improve generally and to enhance the utility of devices of that type to which the present 30 invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:—

Figure 1 shows the invention in side elevation;

Fig. 2 is a side elevation, the view point 45 in Fig. 2 being 90° remote from the view point in Fig. 1;

Fig. 3 is a longitudinal section of the cylinders, parts appearing in elevation;

Fig. 4 is a sectional detail showing the 50 mixing chamber and associated parts.

The engine herein disclosed may be used as a stationary structure or as a marine prime

mover, and may be disposed either horizontally or vertically. In the following description, it will be presupposed that the engine 55 is placed vertically as shown in the drawings, the terms "upper," "lower" and the like being selected accordingly.

In carrying out the invention there is provided an upper cylinder 1 and a lower cylinder 2 united by a tubular connection 3 as will be understood best from Fig. 3 of the drawings. Formed upon the lower end of the lower cylinder 2 is a frame 4 coöperating with a base 5 to form bearings 6 in which 65 is journaled for rotation a shaft 7 carrying a fly wheel 8 and provided in its intermediate portion with a crank 9. A pitman 10 is connected with the crank 9 and is pivoted to a piston head 11 which operates in the lower 70 cylinder 2, there being a piston head 12 in the upper cylinder 1, the piston heads 11 and 12 being connected by a rod 14 mounted to slide in the tubular connection 3 between the cylinders. The rod 14 may be surrounded by 75 packing rings 15 coöperating with the tubular connection 3.

To the cylinders 1 and 2 are secured guides 16 in which is mounted to reciprocate a rod 17 provided at its lower end with an eccentric strap 18 surrounding an eccentric 80 19 secured to the shaft 7. The lower end of the upper cylinder 1 is provided with an exhaust port 20 and the upper end of the lower cylinder 2 is provided with an exhaust 85 port 21. The exhaust port 20 is controlled by a spring-closed valve 22 and the exhaust port 21 is controlled by a similar valve 23. Secured to the rod 17 and projecting inwardly therefrom are arms 24, adapted respectively to engage successively with the valves 22 and 23. Secured to the cylinders 1 and 2 are brackets 25 constituting fulcrums for levers 26. Inwardly projecting fingers 27 are mounted to slide upon the rod 90 17, compression springs 28 abutting against the fingers 27 and abutting against the superposed guides 16. As indicated at 29, the rod 17 is shouldered below the fingers 27. The construction therefore, is such that 100 when the rod 17 is elevated, the fingers 27 will be elevated off the levers 26. When, however, the rod 17 descends, the springs 28 will expand, holding the fingers 27 in

- contact with the levers 26. From the foregoing it will be observed that the fingers 27 and the levers 26 constitute a switch affording a make and break mechanism where-
 5 by the successive charges in the cylinders 1 and 2 may be ignited, any suitable spark plug mechanism and corresponding parts being resorted to as is common and well known in the art.
- 10 The parts 26 and 27 may carry contact terminals T insulated from the respective parts as shown at I. Any suitable means, however, may be provided for insulating the parts 26 and 27.
- 15 The inner ends of the levers 26 are pivoted to links 30 which, in their turn, are pivoted to a walking beam 31, supported intermediate its ends upon the upper cylinder 1 as indicated at 32. Secured to and up-
 20 standing from the walking beam 31 is a handle 33 adapted to be engaged by a segment 34 which is secured to the upper cylinder 1. Secured to the shaft 7 is an expansible, spring retracted wheel 35 adapted to coact
 25 with a shoe 36 secured to the lower end of a governor rod 37 mounted to slide in brackets 38 which are secured to the lower cylinder 2. A compression spring 39 is interposed between one bracket 38 and the shoe
 30 36 to effect a depression of the shoe and to cause the shoe to coöperate with the expansible wheel 35.
- 35 Extended between the cylinders 1 and 2 is a pipe 40 whereby the explosive mixture is conveyed to the cylinders. Interposed in the pipe 40 are valves 41 which open, respectively toward the cylinders 1 and 2. Connected with the pipe 40 intermediate its ends as shown in Fig. 4 is a tubular mixing
 40 chamber 42 the inner end of which is counterbored as indicated at 43 adjacent the pipe 40. Projecting into the mixing chamber 42 is a gasoline inlet pipe 44, provided with a seat 45, adapted to be engaged by a needle
 45 valve 46 threaded into one end of the mixing chamber 42. The mixing chamber 42 is supplied with a depending air inlet pipe 47 in which is journaled for rotation an air control valve 48. Secured to the outer end
 50 of the needle valve 46 is an arm 49 united pivotally by means of a link 50 with the governor rod 37. The outer end of the air control valve 48 is provided with an arm 51 which is pivoted to a link 100, the latter
 55 being pivoted to the upper end of the rod 37.
- The invention further includes a tank 52 located adjacent the lower cylinder 2 and adapted to contain air under pressure. An upright pipe 53 is located above the air
 60 tank 52 and connects therewith, the pipe 53 being provided with a branch 54 which enters the upper cylinder 1. The pipe 53 is further provided with a branch 55 which enters the lower cylinder 2. At its upper
 65 end, the pipe 53 may be equipped with a

vent 56 controlled by a valve 57. At the point where the branch 55 enters the pipe 53 there is placed a rotary valve 58, a similar rotary valve 59 being located at the junction between the branch 55 and the pipe 53. The stems of the valves 58 and 59 are equipped with cranks 60 and the cranks are connected pivotally by a rod 61, the upper end of which upstands to afford a handle 62.

When the shaft 7 is rotated, the eccentric 75 19 thereon, coöperating with the strap 18, will effect a raising and lowering of the rod 17 in the guides 16. As the rod 17 is raised and lowered, the arms 24 will coöperate alternately with the valves 22 and 23, thus 80 opening the exhaust ports 20 and 21 of the cylinders 1 and 2. When the rod 17 reciprocates, the fingers 27 will have make and break relation with respect to the levers 26, as hereinbefore set forth, explosions in the 85 cylinders 1 and 2 being thereby effected. As hereinbefore set forth, the explosions may be timed by moving the handle 33 upon the segment 34 thereby tilting the levers 26 through the medium of the walking beam 90 31 and the links 30.

Should the engine begin to race, the wheel 35 which is carried by the shaft 7 will expand, coacting with the shoe 36 and effecting a raising of the governor rod 37. When 95 the governor rod 37 is raised, the link 50, coacting with the arm 49, will cause a rotation of the threaded needle valve 46, the same approaching or entering the seat 45, in the gasoline inlet pipe 44. At the same 100 time, the rod 37 through the medium of the link 100 and the arm 51 will rock the valve 48 which is located in the air inlet pipe 47, thereby controlling the air supply. In this manner, the speed of the engine will be accurately and positively governed.

Through the medium of the handle 62, the rod 61 may be actuated, the same operating the cranks 60, and controlling the valves 58 and 59 in the pipe 53, connection 110 being thus established between the pressure tank 52 and the cylinders 1 and 2, through the branches 54 and 55 respectively. The operation above described affects the character of the explosive mixture, at any desired time. Further, the air under pressure, contained in the tank 52 may be used to start the engine, cranking being unnecessary.

The explosion chamber of the upper cylinder 1 is located at the lower end thereof, the explosion chamber of the cylinder 2 being at the upper end of the said cylinder. By this construction, the crank 9 is subjected to equal pressure upon opposite sides 115 of the crank shaft 7 and the engine will operate without jar and as effectively as an engine employing steam.

Obviously, the tank 52 may be pumped up from the cylinders 1 and 2. 120 125 130

This application discloses matter divided out of my co-pending application Serial No. 749,041.

Having thus described the invention, 5 what is claimed is:—

1. An internal combustion engine comprising cylinders; spaced levers and means for supporting the levers; a slidably mounted rod; fingers slidably mounted upon the rod and adapted to engage the respective levers to form switches constituting parts of igniters individual to the cylinders, the rod and the fingers being provided with interengaging elements co-operating to space the fingers from the levers; means for moving the links to effect a timing of the explosions in the cylinders; and means for holding the links in adjusted positions. 10
2. An internal combustion engine comprising cylinders; levers and means for supporting the levers; links connected with the levers; a walking beam pivotally connected with the links; movable switch members adapted to engage the levers and co-operating therewith to form igniters individual to the cylinders; and means for adjusting the position of the walking beam thereby to effect a timing of the spark. 15
3. An internal combustion engine comprising cylinders; levers and means for sup- 20
- porting the levers; links connected with the levers; a slidably mounted rod; fingers slidably mounted upon the rod and coacting with the levers to form switches constituting parts of igniters individual to the cylinders, the fingers and the rod being provided with interengaging elements co-operating to space the fingers from the levers; means for moving the links to effect a timing of the explosions in the cylinders; and means for holding the links in adjusted positions. 25
4. In an internal combustion engine, ignition mechanism comprising a lever; means for supporting the lever intermediate its ends; a link connected with one end of the lever; a walking beam pivoted to the link and provided with a handle; a fixed locking means coacting with the handle to hold the handle in adjusted positions thereby to effect a timing of the explosion; and a movable switch member adapted to come into and out of engagement with the other end of the lever. 30

In testimony that I claim the foregoing 55 as my own, I have hereto affixed my signature in the presence of two witnesses,

FREDERICK E. RUPRIGHT.
